CLAIM

The ornamental design for a magnetic article holder, as shown and described.

DESCRIPTION

FIG. 1 is a perspective view of the magnetic article holder;

FIG. 2 is a side elevational view of the magnetic article holder;

FIG. 3 is a top plan view of the magnetic article holder;
FIG. 4 is a bottom plan view of the magnetic article holder;

FIG. 5 is a side elevational view of the magnetic article holder, opposed to the side in FIG. 2;

FIG. 6 is an end elevational view of the magnetic article holder; and,

FIG. 7 is another end elevational view of the magnetic article holder, opposed to the end in FIG. 6.

FIG. 1

FIG. 2

FIG. 3

FIG. 4

FIG. 5

FIG. 6

FIG. 7
